UNITED STATES PATENT OFFICE.

OTTO BRAUNWARTH, OF NEW YORK, N. Y.

DESIGN FOR A TIRE-TREAD.

49,296.

Specification for Design.

Patented July 4, 1916.

Application filed April 22, 1916. Serial No. 93,033. Term of patent 7 years.

To all whom it may concern:

Be it known that I, OTTO BRAUNWARTH, a citizen of the United States, and a resident of the borough of Bronx, county of Bronx, city and State of New York, have invented a new, original, and ornamental Design for a Tire-Tread, of which the following is a specification, reference being had to the accompanying drawing, forming a part thereof.

The figure is a perspective view of a tire tread in place, showing my new design.

I claim:

The ornamental design for a tire tread as shown.

In testimony whereof I have signed this specification in the presence of two subscribing witnesses.

OTTO BRAUNWARTH.

Witnesses:

W. DAVIS CONRAD,
HENRIETTA FAUST.
